UNITED STATES PATENT OFFICE

PATRICK JOHN WHELAN, OF RENFREW, ONTARIO, CANADA

SMOKING PIPE

Application filed April 2, 1931, Serial No. 527,217, and in Canada April 3, 1930.

- This invention relates to improvements in smoking pipes and is a continuation in part of my previously issued United States Patent No. 1,713,204, dated May 14th, 1929.
- 5 The objects of the invention are to provide a smoking pipe of simple construction that will insure a cool smoke while preventing any nicotine being conveyed through the stem.
- 10 A further object is to provide a pipe of this character that can be manufactured and placed on the market at a very reasonable price.

Yet another object is to provide a simple, 15 handy and cheap device that can be fitted into the bowl of any smoking pipe and which will effectively collect the nicotine and prevent it passing into the mouth of the smoker.

The improvement consists essentially in 20 a substantially saucer-shaped member preferably of light metal formed with a hollow central stem closed at the bottom. The edge of the plate being serrated and provided on opposite sides with notches and also suitably 25 arranged holes therein whereby on being dropped into the bowl of a smoking pipe the top of the device automatically engages with the sides of the bowl and the stem with the bottom of the bowl to form an air space communicating with the bore in the pipe's stem.

With the foregoing and other objects hereinafter more fully referred to, reference is now had to the accompanying drawing in 35 which an example of the invention is disclosed and in which like characters of reference indicate corresponding parts in each figure:

Fig. 1 is a sectional side elevation of a 40 smoking pipe bowl with stem partially broken away.

Fig. 2 is an enlarged perspective detail of the device or nicotine collecting member.

Fig. 3 is a perspective detail of a combined 45 extractor and cleaning rod for the pipe.

Fig. 4 is an enlarged perspective detail of a modified form of the device.

Referring now more particularly to the drawing, A, designates the pipe bowl and B 50 the nicotine collector as a whole adapted to

detachably fit within said bowl as illustrated in Fig. 1.

The device consists of a circular plate 10, preferably saucer-shaped and formed with a hollow stem 11, closed at the bottom. The 55 outer edge of the plate is serrated as at 12, and also notched on opposite sides as at 13, for engagement with the extractor herein-after more fully referred to, while in the plate are holes or openings 14, and 15, for 60 the smoke.

To remove the device, the bent end of the extractor 20, is inserted in one of the notches 14, and 15, to loosen it when it can be readily removed.

In use the member B is dropped into the pipe bowl A and the extremity of the stem 11, engaging with the bottom 16, of the bowl whereby a space 17, is automatically provided between the drop of the member B and the 70 bottom of the bowl, communicating with the bore 18, of the pipe stem 19. When the device is dropped into the pipe, as above explained, the serrated edge 12, will automatically grip the side of the bowl and hold the device securely in position until removed by the extractor 20, and thus overcome the objection to my previously patented nicotine device, 75 which was continually falling out and being lost. This extractor, when the pipe is not 80 in use, can be carried in the bore of the pipe with the bent end protruding. It may also be slotted to hold cleaning means.

In Fig. 4, a modified form of the device is 85 shown with a cone-shaped stem which may be sunk in the bottom of the bowl.

In operation, the device B is dropped into the bowl of a pipe, the stem 11, engages with the bottom thereof and then the pipe is secured and as it is smoked the smoke passes 90 through the openings 14, and 15, and into the cooling space 17, and thence through the bore in the stem, while the nicotine will be caught by the top of the device and, it being saucer-shaped, will flow into the stem 95 from whence it can be readily removed.

It will thus be seen that not only does my improved device provide a cool, dry smoke, but it has the advantage of being adapted to any make of pipe without, in any way, inter- 100

fering with the construction thereof. Furthermore, even when in use, unlike a tube in the stem, it will not injure the wood of a pipe, as it will not, in view of the cooling space 17, become overheated and thus liable to clog the bore of the pipe and finally, it has the distinct advantage of not falling out or moving until it is extracted from the pipe.

As many changes could be made in the above construction and many apparently widely different embodiments of my invention, within the scope of the claims constructed without departing from the spirit or scope thereof, it is intended that all matter contained in the accompanying specification and drawing shall be interpreted as illustrative and not in a limiting sense.

What I claim for my invention is:

1. In an accessory for smoking pipes, a plate-like device removably mounted within the pipe bowl and comprising a disc-like head with holes therein, a combined hollow stem and distance piece integral with said head and adapted to impinge upon the bottom portion of the pipe bowl and retain the head in spaced relationship thereto.
2. The invention according to claim 1, in which the disc-like head of the device is formed with a serrated rim to engage with the pipe bowl.

In witness whereof I hereunto set my hand.

PATRICK JOHN WHELAN.
